To all whom it may concern:

Be it known that I, Richard F. Krause, a citizen of the United States, residing at Massillon, in the county of Stark and State of Ohio, have invented a new, original, and ornamental Design for Covered Deep Fry Pans, of which the following is a specification, reference being had to the accompanying drawing, forming a part hereof.

Fig. 1 is a side elevational view of a covered deep fry pan showing my new design;

Fig. 2 is a side elevational view of the cover portion thereof;

Fig. 3 is a top plan view of that shown in Fig. 1;

Fig. 4 is a top plan view thereof with the cover portion removed; and

Fig. 5 is a bottom plan view thereof.

I claim:

The ornamental design for a covered deep fry pan, substantially as shown.
